(57) **CLAIM**

The ornamental design for a front side cover of a motor scooter, as shown and described.

DESCRIPTION

FIG. 1 is a front view of a front side cover of a motor scooter showing my new design.

FIG. 2 is a plan view thereof.

FIG. 3 is a bottom view thereof.

FIG. 4 is a rear view thereof.

FIG. 5 is a right side view thereof.

FIG. 6 is a perspective view thereof as seen from the right front side.

FIG. 7 is a perspective view thereof as seen from the left front side.

FIG. 8 is a perspective view thereof as seen from the left rear side; and,

FIG. 9 is a perspective view thereof as seen from the right rear side.

The portions shown in dotted lines are not part of the claimed design.
